N°. 1,104.

Richard Barry's Design for a Monument.

Patented May 24, 1859.

Fig. 1.

Des. 1104

Richard Barry, of Boston, Mass.
Letters Patent No. 1104. Dated, May 24, 1854.

The schedule referred to in these Letters Patent and making part of the same.

To all Persons to whom these Presents shall come:

Be it known that I, Richard Barry, of Boston, in the County of Suffolk, and State of Massachusetts, have invented a "New or improved Ornamental Design or configuration for the ornamentation of a Sepulchral Monument," and I do hereby declare that the same is represented in the accompanying drawings marked figures 1 and 2, which respectively are front and rear elevations of an obelisk or monument constructed in accordance with my said design.

In carrying out the same as exhibited a quadrangular obelisk is produced at a short distance above its base to an octangular one and has projections in alto reliev, from the added faces or surfaces, respectively, such projections consisting of a series of sprays of flowers and pedestals for supporting the same and being as shown in the drawings. From each base the collection of flowers springs in the form of a long, running vine.

I claim the ornamental design for the shaft or faces of the obelisk as represented and described.
